UNITED STATES PATENT OFFICE.

FRANK H. SHEPHERD AND EMIL SCHWAB, OF LOWELL, ASSIGNEES TO
JAMES W. TUFTS, OF MEDFORD, MASSACHUSETTS.

DESIGN FOR THE CASING OF A SODA-WATER APPARATUS.

Specification forming part of Design No. 7,913, dated December 1, 1874; application filed November 19, 1874.
[Term of Patent 14 years.]

To all whom it may concern:—

Be it known that we, FRANK H. SHEPHERD and EMIL SCHWAB, of Lowell, in the county of Middlesex and State of Massachusetts, have invented and produced a new and original Design for the Casing of a Soda-Water Apparatus, of which the following is a full, clear, and exact description, reference being had to the accompanying photograph, making part of this specification.

In the photograph, A represents the lower or main portion of the casing of a soda-water apparatus, which is of rectangular form, and is surmounted by a "pitch-roof," B. From the center of the roof B on each side projects a correspondingly-shaped gable, C, a beautiful and unique design being thus produced.

What we claim as our invention, and desire to secure by Letters Patent, is—

The design for the casing of a soda-water apparatus, consisting of the rectangular portion A, with its pitch-roof B, having a gable, C, on each side, substantially as herein shown and described.

Witness our hands this 16th day of November, A. D. 1874.

FRANK H. SHEPHERD,
EMIL SCHWAB.

In presence of—

P. E. TESCHEMACHER,
W. J. CAMBRIDGE.
